GRINDING MACHINE

Frank O. Wells, Greenfield, Mass., assignor to
Carroll E. Adams, Pawtucket, R. I.

Application July 5, 1935, Serial No. 29,940

8 Claims. (Cl. 51—219)

My invention relates to improvements in grinding machines, and more particularly to that type of grinding machine intended for use in the sharpening of drills and taps.

5 An object of my invention is to provide a sharpening machine, combined in a single structure for sharpening drills and taps, that is semi-automatic in its action, which will quickly and efficiently sharpen a drill or tap, and which may 10 be set to accurately grind the cutting edges and the lip clearances of a drill point to the proper angles, and the land faces and flutes of a tap to the proper angles of clearance and hook.

A further object of my invention is to provide 15 means on my machine for grinding corners at the intersections of the faces of the drill point and the sides of the flutes. At the present time, it is customary to grind drills with a sharp corner or edge at these intersections. It has been found 20 by exhaustive experiments that the life and efficiency of a drill may be multiplied many times by rounding or removing these corners or intersections and therefore materially save the cost of purchasing a new drill.

25 These and other objects and advantages of my invention will appear in the accompanying drawings, the specification, and the appended claims.

Broadly, my invention comprises a base member, a motor mounted on the base member, a plurality of grinding wheels secured to and actuated by the motor, chuck and quill means for holding a drill or tap to be ground, adjustable bearing members pivotally secured to the base member in which the quill is slidably secured, cam 30 means on the quill for controlling the movements of the drill or tap against the grinding wheels, means for locating a drill or tap in the quill in proper relation to the cams, and means for dressing the grinding wheels for the purpose of maintaining their faces in a true and sharp condition.

40 A preferred embodiment of my invention is illustrated in the accompanying drawings, in which:

Fig. 1 is a side elevational view of the complete 45 grinding machine, showing the drill locator, motor, grinding wheels, the two pivoted posts, the pivoted housing with quill assembled therein in the right hand post position for grinding the 50 point of a drill, and the housing in the left hand post ready to receive the quill for the purpose of grinding rounded corners of a drill on its edges, or removing them by grinding on a chamfer.

Fig. 2 is an end elevational view of Fig. 1 of the 55 grinding machine illustrating the method of piv-

oting the posts for the purpose of feeding the work to the grinding wheels.

Fig. 3 is a longitudinal sectional view of a drill and chuck assembled in the quill.

Fig. 4 is a cross sectional view on the line 4—4 of Fig. 3.

Fig. 5 is a cross sectional view on the line 5—5 of Fig. 3 illustrating the cam for feeding the drill point across the face of the grinding wheel.

Fig. 6 is a side elevational view of the drill 10 point locator with the quill assembled therein.

Fig. 7 is a plan view of the pivoted housing in which the quill is supported while the drill point is being sharpened.

Fig. 8 is a detailed elevational view of the housing and quill shown in Fig. 7, in the same position as that shown in Fig. 1.

Fig. 9 is a side elevational view of the housing shown in Fig. 7, looking in the direction of the arrows 9—9 in Fig. 7.

Fig. 10 is a plan sectional view on the line 10—10 of Fig. 9.

Fig. 11 is a plan view of the housing used for grinding rounded corners, or forming corners on a chamfer, on a drill point with the quill assembled therein.

Fig. 12 is a detailed elevational view of the housing shown in Fig. 11, in the same position as that shown in Fig. 1.

Figs. 13 and 13^A are plan views of the point 30 of a drill which has been sharpened on this machine.

Figs. 14 and 14^A are side elevational views of the point of the drill shown in Fig. 13 and Fig. 13^A.

Fig. 15 is a partial side elevational view corresponding to Fig. 1 showing the pivoted housing in the right hand post with quill assembled therein and adjusted in position for grinding a tap and the tap rest secured in the left hand post 40 by means of which the flutes of the tap are ground.

Fig. 16 is a side elevational view of the tap rest shown in Fig. 15.

Fig. 17 is a diagrammatic transverse sectional view of a tap illustrating the results obtained by the use of the grinding machine.

Fig. 18 is an elevational view of the adjustable dressing tool used to dress the grinding wheel to the proper shape for rounding the corners of a 50 drill point.

Fig. 19 is a plan view of the dressing tool shown in Fig. 18, and

Fig. 20 is a plan view of the dressing tool used for facing the grinding wheel co-operating with 55

the right hand post for grinding the points of drills and the tapered faces of the lands of taps.

Referring now to the drawings in detail, in which like numerals refer to like parts throughout:

- 5 The base member 1 has mounted thereon the motor 2 to which are secured in the usual manner the grinding wheels 3 and 4, the drill point locator 5, the details of which are shown in Fig. 3 10 in section, and the post 6 which supports the wheel guard 7. A shaft 8 is secured in the base member 1, and the posts 9 and 10 are pivotally secured on this shaft by means of the bearings 11. The extent of swing of the posts 9 and 10 15 on the shaft 8 is controlled by the adjusting screws 12 and 13. The post 10 is formed with the socket 14, in which the shanks of the drill housing turn; also the tap rest, or, the wheel dresser, may be secured by the wing set screw 15. 20 In describing the drawings, the methods and attachments used in the process of sharpening the point of a drill will be first described, then the methods and attachments used in the process of sharpening a tap, and finally the devices used 25 for dressing the grinding wheels.
- Figs. 3, 4, 5, and 6 illustrate the means for holding a drill in the quill and for locating the lips of the drill in proper relation to the cams on the quill and quill housing. The drill 16 is 30 slipped into the spring chuck 17 having spring fingers and held lightly in place by a slight turn on the tightening knob 18. The chuck 17 is formed with the tapered and split end portion 19, which engages the tapered surface 20 of the 35 quill 21, and the tapered and split end portion 22 which is engaged by the tapered surface 23 of the threaded tightening shaft 24 to which the knob 18 is secured. The chuck 17 is formed with the alternately spaced slots 25 and 26, and 40 the ends of the chuck 17 are also formed with slots 27 and 28. This construction permits the fingers of the chuck to be gripped and compressed at each end simultaneously, which results in a firm, double grip on the shank of the drill. 45 The tightening shaft 24 is adjustable in the quill 21 by means of the threads 29, and, by turning the knob 18, the spring ends of the chuck 17 are compressed or expanded to grip or to free the drill. The quill 21 has secured thereto, by 50 means of the set screw 30' at the end opposite the drill point, the cam member 30, formed with oppositely located lobes or ears 31 and having secured in the body 32 the cam or locating pin 33.

While the drill is still lightly held in the chuck, 55 the quill 21 is placed in the bearing portion 34 of the locator 5, and is revolved until the lips of the drill point are engaged in the locator button 35, (see Fig. 6), which is retained in the bearing portion 36 of the locator 5 with the set screw 36'. With the drill point held by the button 35, the quill is pushed forward until the cam 30 impinges against the pin 37, then revolved until pin 33 is brought into engagement with the pin 37. The knob 18 is then turned until the 60 drill 16 is tightly gripped in the chuck 17. This procedure locates the drill in the quill with the lips of the drill point in the proper relation to the cam 30.

After the drill has been properly set in the 70 quill, the quill 21, with the drill 16 gripped therein, is removed from the locator 5 and placed in the pivoted bearing or housing 40, illustrated in Figs. 7, 8, 9, and 10. The bearing 40 is pivotally secured on the post 9 by means of the arm 75 41, pivot bearing 42, and pivot shaft 43. The

axis or center line of the pivot shaft 43 intersects with the axis or center line of the radius to which the cutting edges of the drill point will be ground. The adjusting screw 44, impinging against the lug 45 formed on the post 9, may be set to bring the axis of the housing 40 to any desired angle relative to the face of the grinding wheel 4. For grinding the cutting edges of the drill points, this angle is usually 59 degrees, but may be varied if desired. The adjusting screw 16 44 has a threaded connection in the arm 41 of the quill housing 40, and as the screw 44 is threaded into the arm 41, it impinges against the lug 45 and forces this arm and quill bearing 40 to swing around the pivot shaft 43, as illustrated by the arrow 46 in Fig. 10. The post 9 is also formed with the extending arm 47, to which is secured the cam-engaging rod 48 by means of the clamp 49, stud 50, and screw 49'. The stop lug 51, formed on the pivot bearing 42, 20 co-operates with the adjusting screw 44 to hold the bearing 40 with its axis parallel to the face of the grinding wheel 4 when the wheel is being dressed. In this position, the stop lug 51 is in contact with the post 9, and prevents further 25 movement of the bearing 40. This operation will be more fully explained later. The cam member 52 is secured to the bearing 40 by the set screw 53, and is properly aligned with the bearing 40 and the drill 16 by means of the indicator marks "D-D", on cam and bearing as a reference mark 52' for positioning a drill, see Fig. 9. The cam member 52 is formed with the cam face 54, on which the pin 33 of the double cam 30 rides. In operation, the quill 21 is pushed 35 into the bearing 40 until the pin 33 engages the cam face 54, the quill 21 is then revolved in a clockwise direction by turning the knob 18, and the combined movements of the drill point 16' caused by the action of the arms 31 of cam 30 against the rod 48, and, the pin 33 against the cam 52 will cause the drill point 16' to be ground with the correct angle of cutting lips and the correct eccentric relief or lip clearance.

The cam 30 is held in engagement with the rod 48 by the spring 43', acting on the pivot bearing 42.

For large drills, a larger bearing and cam corresponding to the bearing 40 and the cam 30 are used. This necessitates adjustment of the rod 48. This adjustment is accomplished by loosening the clamp 49 and moving the rod 48 to the proper position. Indicator marks "10" and "20" on the top face of the clamp 49, shown in Fig. 7, assist in the proper location of the rod 48.

The housing 40, carrying the quill 21 and drill 16, is fed toward the grinding wheel 4 by the adjusting screw 12, shown in Figs. 1 and 2, and as the grinding wheel is worn down, the loss in diameter is also compensated by swinging the post 9 inward by the adjusting screw 12.

After the drill point 16' has been ground to the proper angle and relief against the grinding wheel 4, the quill 21 is removed from the bearing 40 and inserted in the bearing 55, illustrated in Figs. 11 and 12. The bearing member 55 is formed with the standard 56 and slide 57. The slide portion 57 is slidably secured in the slide bearing 58, and its position relative to the slide bearing 58 is regulated by the adjusting screw 59. Once properly set, the slide 57 is secured by the set screw 60. The slide bearing 58 is formed with the shank portion 61, which is removably secured in the socket 14 formed in the post 10, by the set screw 75

15. The angle of the axis of the bearing 55 with the face of the wheel 3 may be adjusted by turning the shank 61 in the socket 14 and adjusting the slide 57 with the screw 59. The cam 62 is secured to the bearing 55 by means of the set screw 63. The purpose of the cam is to feed the drill point toward the grinding wheel, in order to form a relieved rounded, or chamfered corner on the drill point 16'. The cam 62 is formed with 10 the cam face 64, on which the pin 33 rides. The quill 21 is inserted in the bearing 55, until the pin 33 is engaged against the cam face 64, then the quill 21 is revolved by turning the knob 18. The grinding wheel 3 is formed with the concave-shaped face 65, and as the drill point 16' is fed 15 forward and backward against and away from the face 65, a relieved rounded corner is formed at the intersection of the faces of the drill point and the sides of the flutes. If the wheel 3 has a 20 flat face, a chamfered corner is formed, as indicated at 16'', in Figs. 13^A and 14^A.

The result of the operations above described is to sharpen the drill 16 with both cutting edges 66 exactly alike as to length and having the same 25 angle with the axis of the drill, as indicated at 67 and 68 in Fig. 14. The angle of lip clearance, or contour of the relief surfaces 69 and 70 back of the cutting edges is the same for both cutting edges. The drill has been shaped with the 30 rounded corners 71 and 72 or, chamfered corners 16'', 16'', both exactly alike. Thus the sharpened drill point has been shaped to be correct according to the best practice in every respect, and in addition, the rounded corners 71 and 72 or, chamfered corners 16'', 16'' increase the efficiency and 35 life of the drill many times.

If it is desired to thin the web of the drill point 16', as indicated at 73 and 74 in Fig. 13, this may be accomplished by the use of the tap rest, indicated in Figs. 15 and 16 in cooperation with the 40 grinding wheel 3'.

Figs. 15, 16, and 17 show the manner in which the machine is used for grinding taps. To grind the tapered end 75 of a tap 76, it is secured in the quill 21 with the face 77 of one of its lands 78 in line with the indicator mark T on the quill 21. (See Fig. 15.) A collar 30', having secured therein the pin 33', is secured to the quill 21 in a similar manner as the cam 30 and pin 33 used for drills. The relief controlling cam 79 is substituted for the 50 drill cam 52, and properly placed in the housing 40 by bringing the indicator marks T T into registration on cam and housing, shown in Fig. 15. The housing 40 is set at the proper angle with the grinding wheel 4 corresponding to the taper of the tap end 77 by the adjusting screw 44, the quill 21 inserted in the housing 40 until the pin 33' engages the face 80 of the cam 79, and the quill 21 turned in a clockwise direction by the knob 18. The tap is moved in and out across the face of the wheel 4 by the cam face 80, thus causing a correct relief, indicated at 81 in Fig. 17, to be ground on the tapered faces of the lands 78. The cam face 80 is cut with a plurality of high points 82 equal in number to the number of lands on the tap to be ground. The housing 40 is fed toward the grinding wheel 4 by the feed screw 12, in the same manner as that employed for drills.

When sharpening taps, the flutes 83 should be 70 re-ground to provide plenty of chip room and the correct "hook" or rake for free cutting. For this operation, the tap 76 is held on the V-shaped tap rest 84, and fed to the narrow formed grinding wheel 3' by the feed screw 13. The tap rest 84 is 75 formed with the round shank 85, which is adjust-

ably secured in the socket 14 of the post 10 by the set screw 15. The angle of the tap rest, relative to the wheel 3', may be adjusted by turning the shank 85 in the socket 14 to provide the correct hook. 5

Figs. 18 and 19 illustrate the dressing device used for dressing the formed wheel which grinds the rounded corners on the drill point. A similar device is used for dressing the formed wheel used in grinding the flutes of taps. The diamond-pointed dressing tool 86 is secured in the swinging support member 87 which is formed with the handle 88 and shaft 89. The shaft portion 89 is pivotally supported in the bearing portion 90 of the adjustable pivot support 91. The pivot support 91 is adjustably secured in the socket member 92 which is formed with the round shank portion 93 and is secured thereby in the socket 14 of the post 10 in a similar manner to that employed for securing the tap rest 76 or the slide-supporting member 58. The center of the pivot 89, relative to the wheel 3, is regulated by the indicator or graduation marks 94 and 95 on the socket member 92 and the pivot-supporting member 90, respectively. 20

The straight faces of the wheels 3 and 4 are dressed with the tool illustrated in Fig. 20. The diamond pointed dressing tool 96 is secured in the reduced end portion 97 of the shaft 98. The shaft 98 is formed with the same diameter as 30 the quill 21, and has formed at the end opposite the diamond point 96 the knurled knob 99. In operation, the shaft 98 is substituted in the housing 40 for the quill 21. The housing 40 is swung around on its pivot 43 in the bearing 42 by the 35 adjusting screw 44 until the curved stop lug 51 engages the post 9. In this position, the axis of the housing 40 is parallel with the face of the wheel 4. The diamond point 96 is fed toward the wheel 4 by the feed screw 12, and the shaft 98 is 40 pushed inward and outward in the bearing 40, thus passing the diamond point 96 back and forth across the face of the wheel 4. The face of wheel 3 may be dressed straight in the same 45 way.

Thus it will be seen that I have provided a machine which will correctly and accurately sharpen both the points and rounded or chamfered corners of drill points and the tapered ends of taps, and means for dressing the grinding 50 wheels employed in these operations to keep them in proper condition at all times for the work which they are designed to accomplish.

It will be observed, with reference to Figs. 13^A and 14^A, that the corner portion, indicated 55 at 16'', is chamfered, instead of being formed curving or rounded, as in Figs. 13 and 14, at 71 and 72.

What I claim is:

1. In a grinding machine, a grinding element, means for operating the same, a pivotally supported post, a pivotally supported housing member on said post, means for rotatably supporting a tool to be ground, as a drill, in the housing member, means when the tool is rotated in 65 the housing member for moving the tool across the grinding element and for simultaneously forming the relief on the tool point, said means comprising a cam on the housing member, rotatably secured thereon for adjustment, a part 70 on the rotatable tool-supporting means engaging said cam, an arm on the pivotally supported post and a second cam on the rotatable tool-supporting means engaging the said arm.

2. In a tool grinding machine, the combina- 75

tion with a grinding element, a movably mounted post, a tool-receiving housing pivotally mounted on said post, an adjustable arm on the post, a tool chuck rotatably mounted in the housing, 5 a cam on the chuck engaging the arm for moving the tool to be ground across the face of the grinding element for imparting a relief surface to the tool, a second cam on the housing and a member on said first cam engaging said second 10 cam for controlling longitudinal movement of said chuck.

3. In combination in a grinding machine, a base member, grinding elements on the base member, means for operating the grinding 15 means, a shaft in said base member, posts pivotally supported on said shaft, members for supporting tools to be ground pivotally supported on said posts, means for positioning the tool-supporting members in angular relation to said 20 grinding elements, means for moving the posts toward and away from the grinding elements, and cam means for imparting a relief for the cutting edges of the tools when the tools are rotated in engagement with said grinding elements.

25 4. In a drill grinding machine, a grinding element having a concave face, a post, a housing pivotally supported on said post, a table slidably supported in said housing, means for adjustably positioning said table relative to the 30 axis of said post, a bearing sleeve on said table, a quill for holding a drill slidably and rotatably supported in said sleeve, a cam on said sleeve, a stud on said quill and in engagement with said cam for imparting longitudinal movement to said 35 drill when said drill is rotated, whereby the shoulders of the drill point will be chamfered with a relief angle identical with the relief angle on the face of the drill point.

5. As a constituent mechanism of a machine 40 of the type described, a drill holder comprising a body, an exterior cylindrical bearing surface free of radial projections at the forward end thereof to provide a bearing extending from the forward end toward the rear of the same, a radially disposed cam at the rear end of the body, a cam follower projecting axially from the front face of the cam, a sleeve for receiving a drill adapted to be centrally positioned in the body, means in the body for constricting the sleeve on the drill and a hand wheel at the rear of the 45 holder operating a screw for actuating said means.

6. A drill sharpening mechanism comprising

5 a grinding wheel, a support movably mounted adjacent thereto having a cylindrical bearing opening therein, a separable drill holder having means unitary therewith for clamping the drill centrally therein in a fixed position and having a forwardly extending cylindrical shank free of radial projections adjacent the forward end thereof and constructed and arranged to fit said bearing and be entered thereinto from the rear side, cam elements on the holder adjacent the 10 rear end thereof, a cam element on the support and a cam element adjacent thereto for cooperating respectively with said elements on the holder for controlling axial and swinging movements of the drill during the grinding operation. 15

7. A drill sharpening mechanism comprising a grinding wheel, a support movably mounted adjacent thereto having a cylindrical bearing opening therein, a separable drill holder having means unitary therewith for clamping the drill centrally 20 therein in a fixed position and having a forwardly extending cylindrical shank free of radial projections adjacent the forward end thereof and constructed and arranged to fit said bearing and be entered thereinto from the rear side, a cam element projecting in a transverse plane at the rear of the holder, a cooperating element adjacent the support cooperating therewith, cooperating cam elements on the forward face of said first mentioned cam element and the rear face of the 30 holder, and means at the rear of the holder for applying rotative movement to the same.

8. A drill sharpening mechanism comprising a grinding wheel, a support movably mounted adjacent thereto having a cylindrical bearing opening therein, a separable drill holder having means unitary therewith for clamping the drill centrally therein in a fixed position and having a forwardly extending cylindrical shank free of radial projections adjacent the forward end thereof and constructed and arranged to fit said bearing and be entered thereinto from the rear side, a cam element projecting in a transverse plane at the rear of the holder, a cooperating element adjacent the support cooperating therewith, cooperating cam elements on the forward face of said first mentioned cam element and the rear face of the holder, and means at the rear of the holder for applying rotative movement to the same comprising a wheel handle effective to operate the drill 40 45 50 clamping means.

FRANK O. WELLS.
